CLAIM

The ornamental design for a LED light, as shown and described.

DESCRIPTION

FIG. 1 is a top and right side perspective view of a LED light showing my design;

FIG. 2 is a bottom and left side perspective view thereof;

FIG. 3 is a bottom and right side perspective view thereof;

FIG. 4 is a bottom perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof;

FIG. 10 is a bottom view thereof; and,

FIG. 11 is a cross-sectional view thereof taken in the direction of line 11 in FIG. 5.

The LED light is shown with a symbolic break in its length. The appearance of any portion of the LED light between the break lines forms no part of the claimed design.

The broken lines in the drawings depict portions of the LED light and form no part of the claimed design.
